UNITED STATES PATENT OFFICE

97,833

DESIGN FOR AN AUTOMOBILE

Homer W. Barnhart, Akron, Ohio

Application December 31, 1934, Serial No. 54,649

Term of patent 7 years

To all whom it may concern:

Be it known that I, Homer W. Barnhart, a citizen of the United States, residing at Akron, in the county of Summit and State of Ohio, have invented a new, original, and ornamental Design for an Automobile, of which the following is a specification, reference being had to the accompanying drawings, forming a part thereof, in which—

The dominant features of my new design for an automobile are shown in solid lines in Figures 1 to 5 of the drawings referred to above.

I claim:

The ornamental design for an automobile, substantially as shown and described.

HOMER W. BARNHART.
